UNITED STATES PATENT OFFICE.

FRANCIS J. DWYER, OF ROCHESTER, NEW YORK.

ROTARY VALVE.

1,320,847.

Specification of Letters Patent. Patented Nov. 4, 1919.

Application filed September 10, 1918. Serial No. 253,428.

To all whom it may concern:

Be it known that I, FRANCIS J. DWYER, a citizen of the United States, and a resident of Rochester, in the county of Monroe and State of New York, have invented new and useful Improvements in Rotary Valves, of which the following is a specification.

This invention relates to valves and has particular reference to rotary valves adapted to be used in connection with internal combustion engines of the reciprocating type although not restricted to this particular application.

An important object of the invention is to provide a valve of the above mentioned character so constructed as to be practically silent in its operation.

A further object of the invention is to provide in a valve of the above mentioned character a means whereby the use of both water and air may be employed as a means for cooling the valve during its operation.

A further object of the invention is to provide in a valve of the above mentioned character a means whereby the maximum compression may be retained within the explosion chamber of an internal combustion engine with which it is particularly adapted to be used.

30 A further object of the invention is to provide in a valve of the above mentioned character a means whereby a single intake passage and a single exhaust passage may be employed in connection with a plurality of valves.

A further object of the invention is to provide in a valve of the above mentioned character a means whereby perfect lubrication of the several working elements employed in connection therewith may be maintained.

45 A further object of the invention is to provide in a valve of the above mentioned character a means whereby the same may be easily assembled with respect to the various elements bearing a close relation thereto which are employed in an internal combustion engine as a whole with which the valve is particularly adapted to be used.

50 A further object of the invention is to provide a valve of the above mentioned character which is durable, cheap to manufacture, and reliable in operation.

Other objects and advantages of the in-

vention will be apparent during the course of the following description.

In the accompanying drawings forming a part of this specification and in which like numerals are employed to designate like parts throughout the same,

Figure 1 is a side elevation of an internal combustion engine having a plurality of valves embodying my invention employed therewith, the engine being shown partly in elevation and partly in section,

Fig. 2 is a perspective view of a valve embodying my invention,

Fig. 3 is a vertical transverse sectional view of an internal combustion engine having the valve embodying my invention associated therewith, the valve being shown in section,

Fig. 4 is a top plan view of a valve housing, which housing is adapted to be used in connection with an internal combustion engine having the valve embodying my invention associated therewith,

Fig. 5 is an end view of Fig. 4,

Fig. 6 is an opposite end view of Fig. 4,

Fig. 7 is a side elevation of an internal combustion engine having a plurality of valves embodying my invention employed therewith, certain elements thereof being shown in section and other elements thereof being shown in elevation, and

Fig. 8 is a diagrammatic view showing the assumed position of a valve embodying my invention during the intake, power, and exhaust strokes of an internal combustion engine with which the valve is particularly adapted to be used.

In the drawings wherein for the purpose of illustration is shown a preferred form of my invention the numeral 10 indicates a crank case having a crank shaft 11, the 75 crank case 10 being preferably formed of aluminium and cast integral with a cylinder block 12. Within the cylinder block 12 there is arranged a cylindrical sleeve 13 which is preferably formed of iron. This 100 sleeve as clearly shown in Fig. 3 is spaced from the inclined wall of the cylinder block 12 to provide a water space 14. Upon the cylinder block 12 there is arranged a housing 15 which housing is provided with a water space 16 which communicates with the water space 14 through passages 17 as clearly shown in Fig. 1. This

housing is further provided with a plurality of screw threaded openings 18 adapted for the reception of spark plugs, not shown. The openings 18 corresponding in number 5 to the number of cylinders of the internal combustion engine with which the valve embodying my invention is particularly adapted to be used. Within the housing 15 there is arranged a rotary valve which valve 10 is indicated as a whole by the numeral 19, the valve 19 being provided with a shaft 20 one end of which is mounted within a journal 21 while the opposite end thereof is mounted within a ball bearing journal 22 15 which journal is supported within a casing 23, the casing 23 being secured to the housing 15 by means of tap screws or the like, not shown, which are adapted to be passed through the openings 25 as clearly shown in 20 Fig. 4. As a means for retaining the housing 15 in position upon the cylinder block 12 there is provided a plurality of elongated bolts 26 which extend upwardly through sleeves 27 provided by one side of the housing 15 as clearly shown in Fig. 1, the sleeves 25 being preferably cast integral with the housing 15 in order to further secure the housing 15 in position. Upon the cylinder block 12 there is provided a plurality of 30 bolts 28 which are passed through a flange 29 carried by a side of the housing 15 opposite the side of the housing upon which the sleeves 27 are disposed. By securing the housing 15 firmly to the engine block 35 or cylinder block 12 as above described and then further securing the casing 23 to the housing I am enabled to thus retain all of the actuated elements arranged within the housing 15 and the casing 23 in a correct 40 relation with respect to the cylinder block 12.

The valve 19 is provided with a by-pass 30 which is semi-circular in cross-section as clearly shown in Fig. 3. By forming the by-pass 30 semi-circular, as clearly shown, I 45 am enabled to utilize the portions 31 of the valve 19 which lie adjacent to the by-pass 30 in order to maintain a gas tight jointure between the interior of the casing 23 and the compression chamber of the cylinder as 50 will be readily understood when considering Fig. 3.

In order to provide a means for supplying air to the valve 19 for the purpose of insuring a perfect cooling of the same I prefer to construct the valve 19 to provide an 55 opening 32 therein which opening communicates directly with the atmosphere through arcuate shape ports 33 provided by the housing 15 when the valve assumes the 60 position clearly shown in Fig. 3. Thus it will be understood that upon each revolution of the valve 19 should the air trapped within the opening 32 become heated to a higher temperature than the surrounding 65 air the heated air being lighter than the

surrounding cooler air will expand and pass from the opening 32 through the port 33 allowing cooler air to enter therein and replace the heated air thus expelled from the valve 19 through the port 33.

In order to provide an adequate sealing means and for the valve 19 I prefer to employ a steel liner 34 which liner is provided with a port 35 which is arranged in alignment with the intake port 36 of the cylinder, 70 as clearly shown in Fig. 1.

The housing 15 is provided with a plurality of intake ports 37 which are arranged between ports of the valve 19 as will be readily understood when considering Figs. 1 80 and 4, one passage being utilized to supply gaseous fuel mixture to two adjacent cylinders. The housing 15 is further provided with an exhaust passage 38 which is arranged centrally with respect to the housing 85 15, this exhaust passage being utilized to expel the exhaust gases from the two centrally located cylinders as will be readily understood when considering Figs. 1 and 4.

As a means for directing exhaust gases 90 from the end cylinders there is provided a pair of exhaust passages 39. These exhaust passages are identical with each other and their function may be readily understood when considering Figs. 1 and 7. It is to be 95 understood that in order to produce a four cycle engine with which the valve embodying my invention is particularly adapted to be used the valves employed are to be geared two to one with respect to the crank shaft 100 and as a means for producing this particular ratio I provide a plurality of worm gears 40 which are mounted upon the shafts 20 of the valves 19. These gears in turn mesh with a series of worm gears one of 105 which is shown in Fig. 7 and indicated by the numeral 41, the worm gears 41 being carried by an elongated shaft 42 having its ends journaled within journal boxes 43 carried at the ends of the casing 23. I preferably journal the ends of the shaft 42 within ball bearings as shown at 44. Upon one end of the shaft 42 there is mounted a worm gear 45 which in turn is driven by the shaft 46 having suitable connection with the crank 115 shaft 11 to produce the desired ratio. It will be further understood that each pair of valves rotate in opposite directions thereby making possible the use of one intake passage 37 for two valves.

In order to supply a suitable cooling agent to the water space 16 I have provided a plurality of openings 47 which openings may be connected either directly or indirectly with the water space 14 or with an 125 external source of supply, not shown.

In use the operation of the device is as follows. As above stated the valves of each pair of cylinders thereof are rotated in opposite directions, the by-passes of which 130

valves are arranged with respect to each other to alternately permit the entrance of fuel mixture into the cylinders and to alternately permit the expulsion of exploded 5 gases from the cylinders. In considering the diagram shown in Fig. 8 the by-pass 30 of the valve 19 is diagrammatically shown by the line 48 as permitting the entrance of gaseous fuel mixture into the cylinder. 10 When the by-pass 30 has assumed the position shown by the dotted line 49 the working stroke of the engine is being executed, the exhaust gases being expelled from the cylinder when the by-pass has assumed the 15 position illustrated by the dotted line 50, thus four complete strokes will have been accomplished upon one complete revolution of the valve.

While I have shown the device embodying 20 my invention as being employed in connection with four cylinders I wish it understood that I do not limit the application to any given number of cylinders, it being equally applicable to any number of cylinders desired. I wish it further understood that the 25 form of my invention herewith shown and described is to be taken as a preferred example of the same, and that various changes in the shape, size, and arrangement of parts 30 may be resorted to without departing from the spirit of the invention or the scope of the subjoined claims.

Having thus described my invention, what 35 I claim as new and desire to secure and protect by Letters Patent of the United States, is:

1. The combination with an internal combustion engine having a plurality of cylinders, said cylinders being provided with a 40 water jacket and a plurality of intake passages, of a housing having communication with said water jacket, a plurality of valves journaled within said housing, said valves being arranged in pairs and having their 45 axis arranged perpendicularly to a vertical

plane passed through the axis of all of said cylinders, means for rotating the valves of each pair in opposite directions whereby a single intake passage may be utilized for directing gaseous fuel mixture into the interior of a pair of said cylinders. 50

2. The combination with an internal combustion engine having a plurality of cylinders, said cylinders being provided with a water jacket, an exhaust passage, and a 55 plurality of intake passages, of a housing having communication with said water jacket, a plurality of valves journaled within said housing, said valves being arranged in pairs having their axis arranged perpendicularly to a vertical plane passed through the axis of all of said cylinders, means for rotating the valves of each pair in opposite directions whereby a single intake passage may be utilized for directing gaseous fuel 60 mixture into adjacent cylinders, said exhaust passages being utilized to direct exhaust gases from adjacent cylinders, and means for intermittently communicating the interior of said valves with the atmosphere. 70

3. The combination with an internal combustion engine having a plurality of cylinders, a detachable housing disposed upon said cylinders, said housing being provided with ports, a plurality of rotatable valves 75 arranged within said housing, said valves being provided with openings adapted to register with and receive air through said ports, a casing secured to said housing and spaced therefrom to provide a chamber, 80 worm gears secured to said valves and arranged within said chamber, a worm meshing with each of said worm gears, means for rotating said worm whereby rotation is imparted to said valves, and means for injecting water into said detachable housing, said means being located directly above each of 85 said rotary valves.

FRANCIS J. DWYER.
